J. HOWARD MURRAY, OF TRENTON, NEW JERSEY, ASSIGNOR TO HIMSELF,
T. S. MURRAY, AND A. JAMESON.

Letters Patent No. 69,361, dated October 1, 1867.

IMPROVED VISE.

The Schedule referred to in these Letters Patent and making part of the same.

TO ALL WHOM IT MAY CONCERN:

Be it known that I, J. HOWARD MURRAY, of Trenton, Mercer county, New Jersey, have invented an improvement in Vises; and I do hereby declare the following to be a full, clear, and exact description of the same.

My invention consists of a nut, combining with the stationary jaw of a vise, and with the usual screw, as fully described hereafter; the whole being so constructed and arranged that the said nut may be readily removed and reinserted.

In order to enable others skilled in the art to make and apply my invention, I will now proceed to describe its construction and operation, reference being had to the accompanying drawing, which forms a part of this specification, and in which—

Figure 1 is a vertical section of a vise with my improvement, and

Figure 2 a transverse vertical section on the line 1-2, fig. 1.

A is the front, and B the rear jaw of the vise; the former having a hollow arm, *a*, which fits snugly, but so as to slide freely in the jaw B. D is a screw-spindle, passing through and arranged to turn in the front of the jaw A, to which it is confined by a set-screw, *a*; the end of the latter fitting in a circular groove in the spindle, at the outer end of which is the usual enlargement *b* and handle *d*. The screwed portion of the spindle projects nearly to the outer end of the hollow arm *a* of the jaw A, its threads being adapted to the internal threads of a nut, E, which is of the peculiar form represented in fig. 2, and the front edge of which bears against shoulders *s s'* on the jaw. The upper wing of this nut fits snugly in a recess, *g*, formed in the inside of the hollow projection *e* of the jaw B, as also does the lower wing *f'*, which is confined by a set-screw, *g*. The upper wing *f*, however, is so rounded at *x*, and the recess in which it fits is so formed, that after removing the screw-spindle and withdrawing the set-screw *g*, the nut may be turned to the position shown by dotted lines, fig. 1, and then readily withdrawn from its place to make way for a new nut, should the latter be required, or for the reinsertion of the old one after being repaired. It will thus be seen that as long as the set-screw *g* remains in its place, and any portion of the screw-spindle D is within the nut, the latter may be considered a permanent part of the jaw B, and that the simple withdrawal of the set-screw and screw-spindle permits the removal of the nut. The jaw B is provided as usual with side flanges *h h*, and a vertical flange, *i*, each having holes for receiving screws, by which the vise is secured to the bench.

I claim as my invention, and desire to secure by Letters Patent—

The stationary jaw of the vise, with its shoulders *s s'*, in combination with the screw D and nut E, the whole being constructed as and for the purpose described.

In testimony whereof I have signed my name to this specification in the presence of two subscribing witnesses.

J. HOWARD MURRAY.
